UNITED STATES PATENT OFFICE

RAY R. HUTCHESON, OF KEW GARDENS, NEW YORK, ASSIGNOR TO WM. DEMUTH & CO.,
A CORPORATION OF NEW YORK

DESIGN FOR A PORTABLE LIGHTER

Application filed December 18, 1931. Serial No. 42,131. Term of patent 3½ years.

To all whom it may concern:

Be it known that I, RAY R. HUTCHESON, a citizen of the United States of America, and a resident of Kew Gardens, county of Queens, and State of New York, have invented a new, original, and ornamental Design for Portable Lighters, of which the following is a specification, reference being had to the accompanying drawings, forming a part thereof.

In the drawings:

Figs. 1 and 2 are front perspective views of the portable lighter, Fig. 1 being taken from the right and Fig. 2 from the left.

I claim:

The ornamental design for a portable lighter substantially as shown.

RAY R. HUTCHESON.
